Witness:

W. L. Wright

UNITED STATES PATENT OFFICE.

HARRY D. BINKS, OF RIVER FOREST, ILLINOIS.

ADJUSTABLE SPRAY NOZZLE.

Application filed March 9, 1921. Serial No. 451,023.

To all whom it may concern:

Be it known that I, HARRY D. BINKS, citizen of the United States, residing at River Forest, in the county of Cook and State of Illinois, have invented certain new and useful Improvements in an Adjustable Spray Nozzle; and I do hereby declare the following to be a full, clear, and exact description of the invention, such as will enable others skilled in the art to which it appertains to make and use the same.

My invention relates to appliances for spraying liquids and in its general objects includes the providing of simple means for adjusting the quantity of the spray and for indicating the adjustment.

Generally speaking, my invention aims to provide a spraying appliance which will afford desirable adjustments without requiring it to be taken apart and without leaving any uncertainty as to the spraying capacity for which the nozzle is adjusted. For this purpose my invention aims to provide a spraying appliance which can readily be manipulated for adjusting the same without taking apart any portion of it, which will permit such adjustment to be made without varying the pressure at which fluid is supplied to the nozzle, and which will readily indicate the rate of spraying for which the nozzle is adjusted. Furthermore, my invention aims to provide an adjustable appliance of this kind employing relatively few and simple parts, to provide simple means for maintaining the desired tight interfitting of the operative parts; also to provide a construction which can readily be adapted to spraying appliances regardless of the desired distances between the mouth of each appliance and the point from which the adjustment can conveniently be made and at which the corresponding adjustment is to be indicated. Still further and more detailed objects will appear from the accompanying drawings, in which—

Fig. 1 is a central and longitudinal section through a spray nozzle embodying my invention and designed for spraying oil.

Fig. 2 is a similar section through a shorter form and one including a different mounting for the portion of the nozzle in which the spray is produced.

Fig. 3 is an end elevation of the nozzle of Fig. 1, taken from the right hand end of the latter figure.

Fig. 4 is a section taken on line 4—4, Fig. 1.

In the embodiment of the drawings, I am showing the volume-adjusting and indicating features of my invention as applied to a spray nozzle or atomizing nozzle of the general type in which a spirally advancing motion is imparted to the liquid before the same reaches the contracted outlet of the nozzle, and in which the spirally advancing liquid is broken up into a spray while it is being forced through this contracted outlet. For this purpose, Fig. 1 shows a construction including a tubular nozzle body 1 recessed at its forward end to afford an annular recess for receiving a flange 3 on the forward end of a cup 4, the bore of which cup forms the whirling chamber in which the liquid is spirally advanced before it is forced out through the outlet 5 of the nozzle. This outlet 5 is quite small in bore compared with the diameter of the whirling chamber 6, and this outlet desirably is in a head 7 threaded upon the forward end of the nozzle body 1 and arranged for clamping the flange 3 against the mouth end of the nozzle body. The liquid which is to be sprayed is supplied under pressure to the bore of this body 1 through a supply pipe 8, and is admitted to the chamber 6 through a plurality of inlets 9 in the side wall of the said cup shaped member, the said inlets being here shown as comprising a pair diametrically opposite each other and substantially tangential of the chamber 6 as shown in Fig. 4.

With the parts thus arranged and with the outer end of the inlets 9 opening freely into the interior of the nozzle body, the liquid supplied through the pipe 8 will first be spirally advanced within the chamber 6 and then broken into a spray while issuing through the outlet 5, and the rate at which the spray issues will be predetermined by the nature of the liquid, the size of the inlets 9 and the pressure under which the liquid is supplied. To change this rate without substituting another cup-shaped member 4 having a different size of inlets and without varying the pressure at which the liquid is supplied, I provide this member 4 with a number of sets of inlets of different sizes and provide a control member arranged for admitting the liquid through only one set of the inlets at a time.

In the present embodiment, Fig. 4 shows

the wall of the cup-shaped member 4 as having a second pair of inlets 10 of a larger bore than the inlets 9, and a further set of inlets 11 of a still larger bore, all of these inlets being disposed substantially tangential of the whirling chamber 6. To control these three sets of inlets selectively, I provide a control member having a cup-shaped end 12 sleeved upon and snugly housing the exterior of the cup shaped member 4 and having a single pair of ports 13 adapted to aline interchangeably with the inlet ends of the three sets of inlets. This control cup 12 is fast upon a stem 14 which extends through the rear end of the nozzle body and which can be rotated by means of a knob 15 pinned to its outer end. By using this knob for manually rotating the control member, I can bring the ports 13 into alinement with the entrance ends of any one of the plurality of sets of inlets, namely the inlets 9, 10 or 11, thereby varying the rate at which liquid is admitted to the whirling chamber and correspondingly varying the rate at which the spray is emitted from the nozzle. Then I also provide means associated with the control member for indicating the position to which the latter is adjusted, and desirably for indicating this in terms of the quantity of liquid which will be emitted in a form of spray when the liquid is supplied at a given pressure. For example, I may fasten an indicating pin 16 to the stem 14 of the control member between the knob 15 and the rear of the nozzle body and may provide markings on the rear end of the appliance alining respectively with the indicator 16 according as the control member has its ports opposite one or another of the said sets of inlets. For example, Fig. 3 shows a rear view of an oil burning spray nozzle having inlets designed respectively for furnishing one, three and eight gallons of oil spray, and shows at a glance that the control member is in the position in which the nozzle will deliver one gallon of spray in a given time at the predetermined pressure.

To keep the supply of fluid from leaking through to the other inlets, I desirably form the exterior of the cup shaped member 4 and the adjacent portion 12 of the control member so that these will snugly fit one another, as by providing both of these with similarly tapered and interfitting frusto-conical surfaces. I also desirably provide means for pressing these portions against each other to maintain a tight fit, for which purpose I am here showing a compression spring 17 interposed between the rear end of the nozzle body 1 and a pin 18 which projects laterally from the stem 14. Then I am also showing the rear end of the nozzle body as provided with a stuffing box through which the stem 14 extends, this box includ-

ing a packing 19 held in place by a bushing 20 threaded upon the nozzle body.

With the appliance thus constructed, it will be obvious that with any given pressure of liquid the volume of the delivered spray per minute will depend on the size of the inlets with which the ports in the control members are alined, and that after these respective volumes have been ascertained and the indicating portion on the rear end of the appliance has been correspondingly marked, even an inexperienced helper can readily manipulate the appliance without any uncertainty as to the rate at which the spray is delivered. Moreover, the desired adjustment can instantly be made without the use of any tools, thereby avoiding all loss of time. For example, in using oil as the fuel for heating kilns it may be necessary at first to produce a relatively low temperature so as to evaporate the moisture in the clay without cracking the molded pieces, for which purpose the one gallon rate indicated by the adjustment of Fig. 3 may be ample with a given size and arrangement of spray nozzles and a given pressure at which the oil (or rather the mixture of oil and air) are supplied. When the moisture has thus been driven out, the knob 20 can instantly be turned so as to bring the pointer 16 opposite the mark 3, thereby adjusting the nozzle to the correspondingly higher rate of spray and producing a correspondingly higher intermediate temperature, after which the knob can be turned further on to the "8" to spray the oil at the rate required for the maximum heating of the kiln.

However, while I have heretofore illustrated and described my invention as employed in connection with an oil spraying nozzle used for the heating of a kiln, I do not wish to be limited to this particular embodiment or use of the same, as my invention could obviously be used for many purposes without departing from its spirit. So also, while I have shown a construction including a long tubular body 1 adapted to extend for a considerable distance into a kiln or furnace and have shown the whirling or spray producing chamber as formed within a cup-shaped member having a flange clamped between the nozzle body and the forward head of the nozzle, I do not wish to be limited to these or other details of the construction and arrangement, it being obvious that the same might be varied in many respects without departing from the spirit of my invention or from the appended claims. For example, Fig. 2 shows another embodiment including a relatively short nozzle body 25 having a forward cap 23 threaded into the bore of the nozzle body and having the flange 21 of the cup-shaped member threaded into the cap 23. In this case, the cup-shaped member is desirably

provided with a stem 22 terminating in a square end 24 which extends rearwardly beyond the open end of the cap 23, so as to permit this member to be screwed into position, or unscrewed if desired.

I claim as my invention:

1. In a spray nozzle, a casing enlarged at one end and having an outlet, a cup-like member fixedly secured within the casing 10 with its open end facing and communicating with the outlet and having its periphery spaced from the casing interior, said cup-like member having a plurality of pairs of lateral ports extending from its interior 15 through its periphery, and a rotatable stem in the casing having a cup-shaped end rotatably mounted over the periphery of the cup-shaped member and having a single pair of ports for selective register with the respective ports of a pair of ports of the cup-shaped member.

2. In a spray nozzle, a casing having an outlet, a hollow member in the casing having its open end communicating with the 25 outlet and having a series of lateral ports

extending from its interior through its periphery, and a rotatable stem in the casing having a part thereon rotatably mounted over the periphery of the hollow member and having a port for selective register with 30 the ports of said hollow member.

3. In a spray nozzle, a casing, a head secured to the casing and having an outlet and an interior threaded part, a cup-shaped member having a flange threaded into engagement with the threaded part of the head and having a stem formed to enable screwing of the member into position in the casing, said member having a series of ports 35 extending from its interior through its periphery, and a rotatable stem in the casing having a cup-shaped part rotatably engaged over the periphery of the cup-shaped member and over the stem of the latter and having a port for selective register with one 40 of the ports of the cup-shaped member.

Signed at Chicago, Illinois, March 7th, 1921.

HARRY D. BINKS.
